[57] CLAIM

The ornamental design for a dual-chamber bird feeder, as shown and described.

DESCRIPTION

FIG. 1 is a front elevational view of a dual chamber bird feeder showing my new design; the rear being a mirror image of the view shown;

FIG. 2 is a side elevational view thereof, the opposite side being a mirror image of the side shown;

FIG. 3 is a top plan view thereof;

FIG. 4 is a bottom plan view thereof; and,

FIG. 5 is a cross sectional view taken on line 5—5 of FIG. 2.

FIG. 4

FIG. 1

FIG. 3

FIG. 2

FIG. 5
